SHOE-LASTING DEVICE

Application filed January 17, 1929. Serial No. 333,147.

This invention relates to a shoe lasting device, and has for its principal object the provision of a simple, inexpensive and satisfactory device for securing parts of a shoe temporarily in position during the lasting of the shoe.

Another object is the provision of a device so designed and constructed that the shoe laster may accomplish by one operation and 10 in a very short space of time the result which has formerly required several operations and a considerably longer amount of time.

Still another object is the provision of a securing device which is not consumed or 15 rendered useless after being employed once, but which may be utilized over and over again.

A further object is the provision of a single unitary device to take the place of a comparatively large number of tacks, which may 20 be applied quickly and easily, and which may be removed after use much more quickly and easily than the tacks previously employed for this purpose.

To these and other ends the invention relates 25 in certain improvements and combinations of parts, all as will be hereinafter more fully described, the novel features being pointed out in the claims at the end of this specification.

30 In the drawings:

Fig. 1 is a plan view of portions of a shoe at one stage into the lasting thereof, illustrating the invention applied thereto;

Fig. 2 is a vertical section taken longitudinally substantially through the center of 35 Fig. 1;

Fig. 3 is a bottom plan view of a device constructed in accordance with a preferred embodiment of the invention;

40 Fig. 4 is a side elevation thereof, and Fig. 5 is a perspective view thereof.

Similar reference numerals throughout the several views indicate the same parts.

In Fig. 2 there is illustrated a shoe last 10 which may be of any suitable construction, either entirely of wood or entirely of metal, or partly of wood and partly of metal. In the manufacture of the shoe, an insole 11 is ordinarily placed on the top of this last as 45 shown in Fig. 2, the last being in inverted po-

sition as illustrated. The lining of the shoe, usually of fabric, is shown at 12, while the layer of leather or other material forming the upper of the shoe is illustrated at 13. Ordinarily a toe box 14 of relatively stiff material 55 is placed between the upper 13 and the lining 12 in the toe portion of the shoe, in order to stiffen this toe portion and to cause it to maintain the desired shape.

During the lasting of the shoe, the upper 60 edges of the layers 12, 13 and 14 are brought up over the insole 11 and turned over to lie on the upper surface of this insole. Often these layers are secured to the insole by cement, and usually they are temporarily fastened to the insole by tacks, either for holding the parts in position while the cement hardens, or for any other purpose desired. Tacks for holding the upper and lining to the 65 insole along the sides of the shoe are illustrated at 15 in Fig. 1.

There are certain objections to the use of tacks, however, and these objections are more pronounced at the toe of the shoe than along the sides. On account of the curvature of 70 the toe, the upper and lining are apt to pucker or form pleats between the tacks, and it is difficult to hold the parts in proper position by tacks. Furthermore, a portion of the upper or lining may slip while tacks are being 75 placed in another portion. Placing the tacks requires a considerable length of time and necessitates striking of a considerable number of blows by the operator. When the tacks have served their purpose, they must 80 be removed, which again requires a considerable length of time since each tack must be taken out individually. After being used 85 once, the tacks are usually bent or injured so that they may not be used over again, and thus the expense of tacks alone in a large 90 shoe factory is considerable. In some instances, it may be impossible or undesirable to remove some of the tacks and those which remain are apt to be struck by the needle during 95 subsequent sewing operations, so that the needle may be broken or bent.

It is to obviate these objections and unsatisfactory features inherent in the use of tacks that the present invention has been designed. 100

According to this invention, a unitary device is provided to take the place of a considerable number of tacks. This device is used to hold the parts temporarily in proper position, just as the tacks have heretofore been used for this purpose, but the device of the present invention may be applied in a fraction of the time required to apply the tacks which it replaces, and it may be removed instantly by one operation, thus again saving time, and it may be used over and over again, which is important from the standpoint of economy.

A preferred embodiment of this novel device is illustrated in Figs. 3, 4 and 5, from which it will be seen that it comprises a body portion 20 in the form of a plate having a somewhat U-shaped outline. A flange 21 depends from this plate along the U-shaped sides thereof, but not across the other side which joins the ends of the U-shaped sides. A series of sharp points 22 depend from the lower edge of this flange 21, at short intervals along the flange. Preferably, the plate 20, the flange 21, and the points 22 are all made from a single integral piece of sheet material, which may be stamped and bent into the proper shape easily, quickly, and economically. If desired, however, the points may be constructed of separate pieces of material secured in any suitable manner to the plate or body portion.

In operation, the layers 12, 13 and 14 are pulled over the edge of the insole 11 and wiped in and held down against the insole, either by hand or by the jaws of a lasting machine. A device constructed according to the present invention is then placed on the toe of the shoe, as illustrated in Fig. 1, and the operator strikes it with his hammer, which causes the sharp points 22 to pierce the upper and project into the insole 11 in the manner shown in Fig. 2. Ordinarily a single blow of the hammer is sufficient to drive the device to its proper position, whereas a dozen or so tacks which this device replaces would require at least a dozen blows of the hammer, taking considerably more of the operator's time.

Not only does the use of this device save time, but it actually holds the upper, lining, and toe box more accurately and securely in position than could be done by tacks. The depending flange 21, when the plate is driven down, comes into contact with the upper and smooths or flattens down those portions of the upper which are between the points 22, thus helping to eliminate puckers and pleats, and making a more satisfactory toe construction. Furthermore, it fastens all parts of the toe at once, eliminating the possibility of part of the material slipping while another part is being tacked.

When the cement uniting the upper, lining, and toe box to the insole has set, or when for any other reason this temporary securing means has served its purpose, the device may

then be removed. This is accomplished instantly and easily simply by inserting any suitable member in the space between the plate 20 and the insole 11, along the rear side of the device, and prying the device upwardly. Thus the time necessary to remove individually a dozen or so tacks is saved. Furthermore, the device is not injured in use and may be used over and over again repeatedly. After the device has been removed from the shoe the making of the shoe may be completed in the usual manner, and need not be described here in detail.

The dimensions and proportions of the device may be varied according to requirements. The shape or outline of the device will naturally depend on the shape of the last of the shoe. The points 22 may be made of any desired length, so that they will pass part way through the insole 11, as shown in Fig. 2, or so that they may pass entirely through the insole and partly into the last, if preferred. The flange 21 serves as a stop limiting the downward movement of the device, so that the body portion or plate 20 will always be spaced somewhat from the insole, thus always providing a space between the plate and the insole in which a member may be inserted to pry the device loose. A similar device may be constructed for use in lasting the heel of the shoe or any other portion thereof, although the invention is here illustrated in connection with the lasting of the toe, this being a preferred embodiment.

While one embodiment of the invention has been disclosed, it is to be understood that the inventive idea may be carried out in a number of ways. This application is therefore not to be limited to the precise details shown, but is intended to cover all variations and modifications thereof falling within the spirit of the invention or the scope of the appended claims.

I claim as my invention:

1. A shoe lasting device comprising a body portion substantially in the form of a relatively rigid plate, and a multiplicity of points attached thereto, said points being arranged to be forced through the upper by a blow struck on the body portion, for securing the upper temporarily in position during the lasting of the shoe.

2. A shoe lasting device comprising a body portion in the form of a relatively rigid plate and a series of points secured thereto, said points being located along a substantially U-shaped line and being arranged to be driven through a shoe upper by a blow struck on said body portion, for securing the upper temporarily in position.

3. A shoe lasting device comprising a body portion, a flange depending therefrom, and a series of points projecting downwardly from the lower edge of said flange and arranged to be driven into a shoe upper by a blow struck

on said body portion, for securing the upper temporarily in position, said flange serving to limit the downward motion of said device and to flatten the portions of said upper between said points.

5 4. A shoe lasting device comprising a body portion in the form of a relatively rigid plate having a substantially U-shaped outline, and a series of points projecting downwardly therefrom adjacent the edges of said plate, said points being arranged to be driven as a unit through a shoe upper by a blow struck on said plate, to secure the upper temporarily in position during the lasting of the shoe.
